UNITED STATES PATENT OFFICE.

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND.

CONNECTER FOR WRIST-WATCH STRAP, BAND, OR BRACELET.

Application filed January 14, 1928. Serial No. 246,787.

This invention relates to an improved connector for attaching straps, bands and bracelets to wrist-watches, and particularly to means for rendering the device adjustable to fit different forms of bails as provided on different styles of watch-cases.

A principal object of the invention is to provide a connector or attaching-device adapted to engage with the cross-bar forming part of the bail or loop on a wrist-watch case, and having means for adjusting the width of the engaging portion of the connector in accordance with varying lengths of cross-bars used on different types of watch-cases.

Another object of the invention is to provide a device of the type specified which is capable of adjustment through the substitution of one part or element for another without requiring the use of tools or instruments to fit the connector to the bail of the watch.

Another object of the invention is to provide a device of the type specified wherein the adjusting-means forms a continuation of the connector or attaching-device itself without revealing unsightly joints or obtrusive mechanical projections.

Another object of the invention is to provide a device of the type specified which is strong and rigid in construction and not liable to become detached or deranged when applied to use on the watch.

Another object of the invention is to provide a device of the type specified which is simple in construction, economical to manufacture and convenient to apply for the purpose specified.

Further objects of the improvement are set forth in the following specification which describes a preferred form of construction of the device as illustrated by way of example in the accompanying drawings.

In the drawings:

Fig. 1 is a perspective view showing a conventional form of wrist-watch having a metal strap or bracelet connected thereto by means of the present improved attaching-device;

Fig. 2 is a greatly enlarged plan view of the attaching-device showing a portion of the connector in section and illustrating it as attached to the cross-bar of the bail on the wrist-watch case;

Fig. 3 is a composite view illustrating the several parts of the attaching-device and its adjusting-means in disassembled relation with respect to the bail of the watch-case; and

Fig. 4 is a longitudinal sectional view illustrating one form of tubular cross-bar or bail element adapted for use with the present improved connector or attaching-device.

Referring to the drawings, the present improved device comprises in general a hook or loop-member which may be formed as a part of or fastened to the end of the wrist-watch strap, band or bracelet to adapt it to engage with the cross-bar forming a part of the bail on the side of the watch-case; the connector loop being of a definite width and adapted to be used in conjunction with spacer-hubs or bosses held in place at the sides of the loop by means of a tie or connecting strip.

Fig. 1 of the drawings illustrates the watch-case 2 as of conventional oblong or part-hexagonal shape and provided with the usual attaching loops or bails 3 on its sides. The bails 3 are generally constructed with opposite parallel lugs or ears 4 projecting from the sides of the watch-case 2 and provided with suitable holes for receiving the ends of the cross-bar 5, see Fig. 3, which constitutes the connecting member for the strap, band or bracelet. As illustrated in Fig. 4, the cross-bar 5 is constructed as a tubular shell of proper length to fit between the two ears 4 on the side of the watch-case 2 and having telescopic projections or pintles 6 at its ends for engaging the holes in the ears to fasten the bar in place. This form of cross-bar is of usual construction and its method of operation adapts it to be inserted through a loop at the end of a strap, band or bracelet and then engaged with the

ears on the watch-case in attaching the strap thereto while providing for the disconnection of the strap when required.

The present improved connector or attaching-device is adapted for use more particularly with metal straps, bands and bracelets such as are now generally in vogue, especially for gentlemen's wrist watches. The watch-cases are made in many different shapes and sizes and consequently the bails on the sides thereof are not of uniform width. It is desirable, however, that the metal straps, bands and bracelets be made of a standard width and adapted for attachment to bails of different types on the many styles of watches handled by retailers. The present attaching-device accomplishes this object through the use of an improved adjustable connector as next described.

Fig. 1 illustrates the wrist-watch strap or bracelet as comprising two lengths or sections of a metal band 10 which may be joined at their overlapping ends by any suitable clasping means 11 to adapt the strap to be adjusted in length to fit the wrist of the wearer. Each strap-length 10 is provided at its opposite end with a hook or loop 12, see Fig. 3, which may be formed by bending the metal into cylindrical shape. In other cases where the band or bracelet is constructed of reticulated metal fabric, such as wire mesh, the connector or loop-member may comprise a separate element suitably attached by soldering or otherwise to the end of the band. The hook or loop 12 is adapted to receive the cross-bar 5 which, with the ears 4, forms the bail on the side of the watch-case 2, and obviously this part must be adapted to engage around the bar with its sides in abutting relation with respect to the ears 4 in order that it may be connected neatly with the bail without side play thereon.

Where the cross-bar 5 of the bail is of a length corresponding to the width of the loop 12 on the band or bracelet no adjusting means is required, but in many cases, particularly on gentlemen's watches, the cross-bar of the bail is much longer than required for the width of the strap. Therefore, to adapt the connector to be used with long bars I provide attachable spacer-hubs or bushings 14 which may be fitted to the cross-bar 5 to fill the space between the sides of the loop 12 and the ears 4. These spacer-hubs or bushings 14 may be made in graduated widths in accordance with the varying lengths of the cross-bars on different types of watches, but obviously it would be inconvenient to provide such hubs or bushings as separate elements for individual application to the fastening-device. That is to say, such hubs or bushings must be quite small and if used separately they would be inconvenient to handle in fitting them in

place and apt to become lost in shipping or handling.

The present invention therefore contemplates the provision of pairs of associated spacer-hubs or bushings connected together in the form of a single element adapted for convenient handling and application in fitting the attaching-device or connector, to the bail of the wrist-watch. As illustrated in Figs. 2 and 3 of the drawings, the spacer-hubs or bushings 14 may be connected by a tie comprising a relatively narrow strip of metal 15 formed integral with the hubs. Conveniently, the complete adjusting element is preferably constructed from flat stock rolled into the form shown, or it might be made from a single length of tubing cut away at the center to leave a narrow strip or tie 15 connecting the hub-portions 14 at its ends. The connecting strip 15 is bent or bowed outwardly in offset relation to adapt it to overlie the inturned end-portion 16 of the hook or loop 12, and the opposite sides of the hook are preferably cut away to form notches 17 for the reception of the bent-portions 18 of the strip. Through such engagement of the bent-portions 18 of the strip 15 in the notches 17 the end-hubs or bushings 14 are held firmly in place on the loop 12 and prevented from turning after the connector has once been attached to the cross-bar 5 of the bail on the watch-case.

My improved connector or attaching-device is applied to use in the manner as next explained: When the strap or bracelet 10 is of a width corresponding to the length of the cross-bars 5 in the bails on the watch-case the strap may be connected to the bails by simply removing their cross-bars in the manner as previously explained, inserting them through the loops 12 and then replacing the bars by telescoping their end-pintles 6 to permit them to be inserted into the holes in the ears 4. In cases where the cross-bars 5 are longer than the width of the strap or band 10 an adjusting device is employed of suitable width to fill the gaps between the sides of the connector and the ears 4. As before stated these adjusting elements may be made in varying sizes in accordance with cross-bars of different lengths and since they are of relatively light weight and economical to manufacture a supply of graduated sizes may be furnished, say three or four, with each wrist-watch strap or bracelet.

In most cases the jeweler or other retailer selling the watches and bracelets will be supplied with sets of adjusting-devices in graduated sizes, and to fit the strap or bracelet connector to the watch bail is a simple and easy matter. After determining the difference between the width of the strap or bracelet and the length of the cross-bar in the bail of the watch the

proper size of adjusting-member is selected and placed in position on the loop or hook 12 of the connector. This is done by simply straddling the adjusting-member across the 5 loop or hook 12 with its hub-portions 14 abutting the sides thereof. The connecting strip 15 which has an inherent spring tendency will thus be caused to snap into the notches 17 at the sides of the loop 12 so that the whole device is held fixedly in place 10 thereon. The cross-bar 5 is then inserted through the spacer-hubs 14 and loop 12 with its ends substantially flush with the ends of the opposite hubs. All that is then required 15 is to telescope the pintles 6 within the ends of the tubular bar 5 whereby the latter may be placed between the ears 4 to allow the pintles to engage with the holes therein, this operation being performed in the usual 20 manner by first inserting one of the pintles through the hole in one ear and then compressing or telescoping the other pintle by means of a knife-blade, pin or other suitable instrument to cause it to slide into 25 position to engage in the other ear.

It will be observed from the foregoing that my invention provides a particularly simple and neat connector or fastening-device for attaching straps, bands, bracelets 30 and the like to the bails of wrist-watches, and one which is readily adjustable in width to adapt it for use on various types of wrist-watches which have bails with cross-bars of different lengths. When 35 applied to use the adjusting means or spacer-hubs 14 at the sides of the loop or hook 12 of the connector form a continuation thereof, and being held snugly in place by the resilient cross-strip 15 they have the 40 appearance of being constructed integral therewith. In other words, there are no unsightly seams, joints, shoulders or other mechanical deficiencies visible to mar the smooth and finished appearance of the 45 device or to render it bulky and cumbersome.

Moreover, the improved device is extremely simple and economical to manufacture and proof against derangement or 50 getting out of order to render it durable in use over long periods.

While I have herein described and illustrated a preferred form of construction of the improved attaching-device it is to be 55 understood that various modifications may be made in the structure and arrangement of the parts thereof without departing from the spirit or scope of the invention.

Therefore, without limiting myself in 60 this respect, I claim:

1. In a connector for attaching wrist-watch straps, bands and bracelets to the bails of a watch-case, the combination of a loop at the 65 end of the strap, band or bracelet for engaging around the cross-bar of the bail, spacer-

hubs applied to the sides of the loop to adapt it to conform to the length of the cross-bar, and means for detachably securing said spacer-hubs to the loop.

2. In a device of the type specified, the combination with a wrist-watch having a bail on its side comprising projecting ears and a cross-bar extending therebetween, of a connector comprising a loop through which the cross-bar is inserted to attach a strap, 75 band or bracelet to the watch, spacer-hubs adapted to fit the ends of the cross-bar abutting the opposite sides of the connector loop, and means connecting the hubs to hold them in alinement to adapt them to be 80 readily attached to the connector-loop.

3. In a device of the type specified, the combination with the bail of a wrist-watch comprising ears projecting from the side thereof with a cross-bar extending therebetween, of a connector for attaching a strap, band or bracelet to the watch, said connector having a loop adapted to engage around the cross-bar of the bail on the watch, and an 85 adjusting element for extending the width 90 of the connector-loop to conform to cross-bars of different length, said adjusting element comprising a pair of opposite tubular hubs connected by a cross-tie whereby to adapt the hubs to be placed in abutting relation with the sides of the connector-loop with the cross-tie extending thereacross to retain the hubs in place.

4. In a device of the type specified, the combination with a wrist-watch having a 100 bail on its side comprising a cross-bar, of a connector for connecting a strap, band or bracelet to the watch, said connector comprising a loop for receiving the cross-bar of the bail on the watch-case and formed with 105 notches at its sides, and an adjusting device for extending the connector-loop to conform to the length of the cross-bar in the bail, said adjusting device comprising a pair of tubular hubs adapted to abut the sides of the 110 connector-loop to form continuations thereof and provided with a relatively thin cross-strip bowed into offset relation with respect to the hubs to adapt it to extend across the loop with its ends engaging the notches 115 therein in the manner and for the purpose substantially as described.

5. In a device of the type specified, the combination with a wrist-watch having a 120 bail on its side provided with a cross-bar, of a connector for connecting a strap, band or bracelet to the watch comprising a substantially cylindrical loop for receiving the cross-bar of the watch-bail, said loop cut away at its ends to form notches, and an 125 adjusting device for extending the width of the connector-loop comprising a pair of spacer hubs adapted to abut the sides of the loop to enclose the cross-bar of the bail on the watch and having resilient means extending 130

ing between the hubs and adapted to lie across the loop with its ends yieldingly engaging the notches therein to detachably hold the spacer-hubs in position at the sides of the connector-loop.

5. The combination of a wrist watch having a pair of lugs to receive a pin, a bracelet wrist band having a loop of a width less than the distance between said lugs, a pin

extending through said loop and lugs to 10 hold the loop in position and an end piece having means for mounting the same on said band and a portion positioned between said band loop and one of said lugs to limit lateral movement of the loop between said lugs. 15

In testimony whereof I affix my signature.

CHARLES H. KESTENMAN.
